UNITED STATES PATENT OFFICE.

JOSEPH B. BAKER, OF NEWTON, MASSACHUSETTS.

PROCESS OF AMPLIFYING ELECTRIC CURRENTS.

SPECIFICATION forming part of Letters Patent No. 660,613, dated October 30, 1900.

Application filed November 23, 1899. Serial No. 738,066. (No model.)

To all whom it may concern:

Be it known that I, JOSEPH B. BAKER, a citizen of the United States, and a resident of Newton, in the county of Middlesex and State 5 of Massachusetts, have invented certain new and useful Improvements in Processes of Amplifying Electric Currents, of which the following is a specification.

Figure 1 is a diagram of a hypothetical field 10 of force. Fig. 2 is a diagram of a unipolar field of force. Fig. 3 is a perspective schematic view of a unipolar motor of the common or Faraday type. Fig. 4 is a diagram of a bipolar field of force. Figs. 5, 6, 7, 8, 9, 10, and 15 11 are each diagrams of different apparatuses which may be used to carry out the process of my invention.

Let us imagine a number of lines of force 20 confined to a single plane and all radiating uniformly from a common central point—such a field of force, for instance, as is represented in Fig. 1. Let us also imagine that we have a straight electrical conductor or piece of copper wire *a*, which is perpendicular to the plane 25 of the lines of force and which revolves about their central or radiating point *o*, thus describing a cylinder having its axis passing through *o* as its center. It is well known and can be readily understood that in such event 30 there is generated in the wire *a* an electromotive force which is constant in amount and direction for each and every position of the wire. As the field is entirely uniform, as the wire cuts each element of the field at exactly 35 the same angle, and as the velocity of rotation is uniform, the electromotive force impressed upon the wire must be constant and the same for any circular point about the center *o*. The wire is always perpendicular to 40 the particular line of force which it cuts, and the direction of motion of the wire at such instant is also perpendicular to such line of force.

A set of lines of force such as has just been described is realized, so far as practical purposes are concerned, at the pole of a bar-magnet. Fig. 2, for instance, illustrates a longitudinal section through the lines of force of a bar-magnet; but in order to get a proper idea of the lines of force about such pole as 50 they exist in space we must imagine the diagram rotated about the central axis NS, when we see that in each plane perpendicular to the

axis there are found lines of force radiating from a central point, just as in Fig. 1. It is plain, therefore, that if a copper wire *a* lying 55 within this field of force be rotated at a uniform rate, so as to remain always parallel to the axis of the magnet and at the same distance therefrom, there will be generated in the wire an electromotive force which is 60 constant in amount and the same for every position of the wire during its rotation. The wire cuts all of the lines of force which it meets substantially at right angles, and the direction of motion of the wire is at right angles 65 to such lines of force which at the instant in question are cut by the wire.

The field of force which I have just described has long since been utilized by Faraday in constructing an electric motor, one 70 form of which is indicated in Fig. 3. There is an annular mercury-bath *b*, in the center of which is mounted the upper pole of a bar-magnet *N*. Conducting-wires *a a* are mounted to rotate on a pivot *c*, and the connections 75 are such that a current may pass from the binding-post *c'* to the pivot *c* through the conducting-wires *a a* in parallel to the mercury-bath and binding-post *b'*. If then the conductors *a* are rotated by mechanical power 80 about the magnet *N*, it is plain that a current will be generated which may be assumed as passing downwardly through each limb of the conductors *a* into the mercury-bath, and thence to the binding-post connected therewith. On the other hand, if the conductors *a* be not rotated by mechanical power, but a current be passed up through the magnet and down through the conductors *a* and mercury-bath, the reactions set up will be such as to 85 cause a uniform rotation of the conductors *a*.

The type of a field of force which I have just been describing, and which has been called the "unipolar" type, is essentially distinct from the type of field of force which I 95 have indicated in Fig. 4 of the drawings, and which may be called the "bipolar" type. The figure shows a field-magnet wound so as to produce a north and south polarity, respectively. The lines of force joining these poles 100 are approximately parallel and are indicated by the dotted lines. If we assume a wire *a* perpendicular to the plane of the figure to be revolving about the central axis *o*, it is clear

that the relation of this wire to the lines of force changes from instant to instant. In the position shown the wire *a* is cutting no lines of force. Farther on in its course the wire 5 will be cutting the lines of force at an acute angle, and when the wire has reached the position which is ninety degrees from that shown it will be cutting the lines of force at right angles. Farther on it will be cutting 10 the lines of force in an opposite sense, so that we see that the wire *a* is the seat of an electromotive force which is not constant, but which is varying from moment to moment and which changes in direction twice for each 15 revolution of the wire.

Now the object of my invention is to repeat gradually varying or alternating signaling-currents and, as a special case, telephonic currents, which, in other words, means that I propose 20 either to amplify the gradually-varying signaling-currents, so as to make their effect more strong, or, what in effect amounts to the same thing, that I propose to generate by means of weak alternating or varying currents other currents which shall be similar in 25 all respects to those first mentioned, but which shall be stronger; and this I accomplish by utilizing the principles above outlined. If then we consider a magnetic field and suppose 30 it to remain unchanged as a whole for a given period of time, it will be plain that we may rotate a conductor within that field in such a manner that the electromotive forces which are generated in the conductor are 35 similar in sign and equal in amount for every position of the conductor within the field—that is to say, so long as the field remains unchanged as a whole the electromotive force induced in the conductor will be independent 40 of the position of the conductor in the field. If, on the other hand, the field as a whole grows more dense or less dense or changes in sign, as it would if it be generated in a whole or in part by an alternating or 45 varying current, it is equally clear that we may so rotate a conductor therein as to have the electromotive force induced in the conductor at any given instant of time proportional 50 to the density of the field and the sign of the electromotive force determined by the sign of the field, so that the electromotive force generated within the conductor shall be entirely independent of the position of the conductor within the field.

Now my invention consists, broadly stated, 55 in the process of amplifying or generating amplified gradually-varying harmonic or alternating signaling-currents by causing a conductor to so move in a magnetic field generated in whole or in part by a signaling-current that during every position in the motion of the conductor electromotive forces similar in sign and equal in amount are generated so long as the field as a whole remains 60 unchanged, variations in the sign or amount of the electromotive force generated in the conductor being determined solely by varia-

tions in the density and sign of the magnetic field taken as a whole and not by the position of the conductor within the field and being proportional thereto. If a system of conductors be employed instead of a single conductor, then not only is the electromotive force generated in the system of conductors as a whole, but the electromotive force generated in each element of the system is the same at each point of the motion so long as the field remains unchanged as a whole, variations in the density of the field causing variations in electromotive forces which are exactly proportional thereto in sign and amount and which are independent of the position of the moving conductor in the field. 70

More specifically stated, my invention consists in the process of amplifying gradually 85 varying or alternating signaling-currents or of generating amplified varying currents by continuously moving a conductor in a magnetic field, so that the motion of the conductor is at each point of its path substantially 90 at right angles to the lines of force which are cut by the conductor at this point. It will thus be seen that by utilizing a varying signaling-current to generate a magnetic field, preferably of the unipolar type, which I have 95 above described, and by causing a conductor to move continuously within this field in the manner above pointed out I can cause to be generated within this conductor an electromotive force, and in consequence a current which shall at each and every instant of time be exactly proportional to the strength 100 of the field generated by the varying current, and that I can thereby generate a largely amplified or reinforced signaling-current 105 without in any way distorting it or changing its character.

Naturally my invention has a most advantageous application in repeating telephone-currents, for the reason, as stated above, that the variations in the sign and amount of the electromotive forces generated in the moving conductor are determined by and are exactly proportional to the variations in sign and amount of the magnetic field generated 110 by the telephone-currents to be repeated. There is therefore no substantial distortion of any kind in the repeated telephone-currents, which are merely amplified pictures of the original currents which generated them. 115 I shall therefore especially claim this feature.

In order that my process may be more fully understood, I proceed to describe a number of apparatuses, each of which may be used in order to carry the process into effect.

In Fig. 5 I have shown the upper pole *N* of a permanent magnet on which is mounted a mercury-cup *e*. This pole *N* is surrounded by a telephone-coil *t*. A shaft *g*, driven by a pulley *g'* and belt *g''*, is mounted in bearings *f*. These bearings may be supplied with ball-races (not shown) or may be of other special design for the purpose of diminishing friction. On the shaft *g* is mounted a 125

yoke-armature h , which may have two or more arms, symmetrically disposed, dipping into an annular mercury-trough i . From the axis of this armature there projects a conducting-pin h' into the mercury-cup e . The armature h must naturally be made of some good conductor, such as brass or copper.

The pole N of the bar-magnet creates a field of force of the unipolar type above described, 10 and the construction and arrangement of the yoke-armature are such that in its motion it continually cuts the lines of force, due to the pole N, at right angles. If, then, the armature be revolved uniformly by the belt 15 and pulley, a current will be generated which may be assumed as passing from the line-wire l to the mercury-cup e up through the pin h' and down through the arms of the yoke-armature h into the mercury-trough i 20 and out to line l . This current, as has been fully pointed out, will be equal in strength for each position of the armature during its rotation. If now a varying signaling telephone-current be passed through the telephone-coil t , the magnetic field will be changed 25 by an amount which is proportional to the strength of the varying current. This change in the strength of the magnetic field will correspondingly change the current flowing 30 through the yoke-armature, such current strength not depending upon the position of the yoke-armature at any point of its revolution, but simply depending on the strength of the varying current, the velocity of rotation 35 being constant. It will be seen, therefore, that there will be generated in the circuit of the yoke-armature a varying signaling or telephone current similar in all respects to the current in the coil, but greater 40 in intensity, and such current may be utilized in any known way. Thus, for instance, the currents in the telephone or signaling coil may be the weak currents coming from a distant station, and the currents in the yoke-armature may be sent to a station farther on, 45 since they have been strengthened. The apparatus of Fig. 5 thus acts as a relay for transmission in one direction only.

It is manifest that instead of rotating the 50 yoke-armature by mechanical power, in which case the pole N need not be permanently magnetized, I may send a constant current through the circuit of this armature from a constant source, such as a battery, by which 55 means the yoke-armature will be set into rotation by the reaction of the currents therein on the magnetic field, as was explained above in connection with the Faraday unipole motor. The change in the intensity of this current by the current in the telephone-coil will take place as before.

The construction and operation of the apparatus shown in Fig. 6 will be clear without much further detailed explanation. There 65 is the same bar-magnet, with its pole end surrounded by a telephone-coil t , having its conductors passing through the center of the

magnet, and the same annular mercury-bath i . So, too, there is the same shaft g , mounted in bearings f and carrying an armature h . 70 This armature, however, is a cage or laminated cylinder having an annular brass contact h^3 at its lower end dipping into the mercury-trough. It acts, in effect, like an infinite number of armatures, such as shown in Fig. 5. The operation of the apparatus is precisely that ascribed to Fig. 5. I may merely add that when the armature is driven by mechanical power it is not essential that the bar should be permanently magnetized. 75 In such case the entire current induced in the armature will be due to the telephone-currents in t .

The apparatus shown in Fig. 7 embodies a different construction. There is a shaft g , 80 mounted in bearings f and driven by a pulley g' . On this shaft g there is mounted a drum h^4 , which is supplied with a helical groove. There is a unipole N, mounted within this drum, which carries a telephone-coil t . Within 85 the helical groove in the drum is placed a helical conductor h^5 , connecting with the shaft g at the upper end and with an annulus h^6 at the lower end. The electric circuit passes through the contact h^10 to the shaft g , 90 the helical conductor h^5 , the annular conductor h^6 , and the ball-bearings h^7 , to a stationary conductor h^8 . The helical conductor h^5 thus 95 rotates bodily in the unipolar field and has developed in it an electromotive force composed at any instant of two parts—namely, the electromotive force due to the speed of rotation and strength of the field acting on a simple wire rotated parallel to the axis of the magnet and constituting the magnetic projection of the "helix," as it is called in the text-books, and the electromotive force due 100 to the mutual induction of the signaling or telephone coil on the helix constituting the armature conductor. From this it will be 105 seen that a weak varying signaling or telephone current passing into the telephone-coil t will by its action upon the magnetic field of the unipole generate currents of an amplified character in the line l . 110

The construction of Fig. 8 embodies a signaling or telephone coil t , surrounding a unipole N. It also embodies a rotating drum h^4 , on which there is wound a conducting-wire, as shown, which passes around and is driven 115 by a pulley H^2 . It will be seen from this construction that the helical conducting-coil h on the drum h^4 acts as does the coil in Fig. 7; but in the construction of the present figure all sliding or movable contacts are dispensed with. The current generated in the helical conductor by the signaling or telephone coil is transmitted by induction to the secondary coil j and thence to line l . The wires may be kept from crowding together at 120 the center of the drums by means of stationary guide-pieces holding the parallel wires apart and guiding them in fixed planes. 125

The construction of Fig. 9 embodies two

separate unipoles N S, each surrounded by a drum h^4 , driven as above described. Signaling or telephone coils $t t$ surround the unipoles. There is an endless conductor h on 5 each of the drums h^4 . Rotation being imparted to the drums and the conductors wound thereon in any suitable manner, the electro-motive forces developed in the coils will at each instant be in opposite directions in the 10 endless conductor. It will be apparent, therefore, that current may be taken from the wires $h h$ by means of the sliding contacts $h^{10} h^{10}$, the current being transmitted to the main line $l l$ by means of an induction-coil L, as 15 shown.

In Fig. 10 I have shown a unipole N, surrounded by a telephone-coil t and a ring-electrode r . The shaft g , mounted in bearings f and rotated as before, carries an electrode r' . 20 Current from a dynamo or battery u is passed through the retardation-coils $R R$ and thence through the shaft g to the electrode r' and across the air-space to the ring-electrode r . The arc may be rotated by a belt and pulley, 25 as shown. The action of the varying field produced by the telephone-coil upon the arc conductor traversing the lines of force of this field at right angles will in all essential respects be the same as was described above for 30 other types of conductors, and reinforced or magnified telephone-currents will be sent to the line $l l$ by means of the induction-coil L, as shown. By this type of construction, embodying a moving arc, the attainment of a 35 high speed is possible, and at the same time I utilize an effective form of moving contact.

The construction of Fig. 11 differs from that shown in Fig. 10—namely, in the fact that the belt and pulley for rotating the electrode 40 are dispensed with, the arc being rotated by means of its reaction against the magnetic field of the unipole, which is excited for this purpose by an exciting-coil e' . Additionally the rotating arc is inclosed by an infusible 45 tube r^2 to prevent any possible rupture of the arc by centrifugal force.

I call attention to the fact that the sliding contact h^{10} in Figs. 7 and 10 bears on the shaft g at a point of little or no motion of the shaft. 50 This is especially important in the construction of Fig. 10, since were the contact h^{10} at a point of much motion of the armature a principal advantage of the use of the electric arc would be rendered of no effect. Suitable 55 provisions will be made against losses by eddy-currents in the mercury-troughs, annular contacts, &c.

I have illustrated the several types of apparatus which I have just described in order 60 to explain the principles of my invention and to show how it may be carried into effect. It will be plain that my invention is not limited to any specific form of apparatus, but covers the process which I have above defined. So, 65 too, it will be readily apparent that many other types of apparatus may be devised which shall carry out my process, those above

described having been merely described by way of example. I believe, however, that I have described a sufficiently-large number of 70 types of apparatus to make the scope of my invention and the lines along which it may be developed clear. I need hardly say that I am not in this application concerned with any details of the apparatus, and as they will 75 be reasonably clear to a skilled workman I have not described them.

In each of the apparatuses which I have shown it will be seen that during every position in the motion of the moving conductor 80 electromotive forces are generated therein which are determined solely by the density and sign of the whole magnetic field at any given instant, and not by the position of the conductor within the magnetic field. This, 85 specifically stated, is due to the fact that the moving conductor is always at right angles to the lines of force which it cuts and to the direction of motion of the moving conductor—that is to say, the conductor, its direction of motion, and the lines of force which are cut at any given instant are all three at 90 right angles to each other or substantially so.

It may be well to again state if I employ a 95 system of moving conductors instead of a single conductor that the same remark is true of each element of the system of conductors, and not merely of the system of conductors as a whole.

What I claim is—

1. The process of generating amplified varying signaling-currents which consists in 100 causing a conductor to so move in a magnetic field, which is generated in whole or in part by the varying signaling-current, that the electromotive force generated in the moving conductor is independent of the position of the conductor within the magnetic field, substantially as described.

2. The process of generating amplified varying signaling-currents which consists in 110 causing a conductor to so move in a magnetic field, which is generated in whole or in part by the varying current, that the electromotive force generated in the conductor is determined solely by variations in the density or 115 sign of the magnetic field, taken as a whole, and not by the position of the conductor within the field, substantially as described.

3. The process of generating amplified varying signaling-currents which consists in 120 causing a conductor to so move in a magnetic field, which is generated in whole or in part by the varying signaling-current, that the conductor, its direction of motion and the 125 line of force which is cut shall at all times be each at right angles to the others, substantially as described.

4. The process of generating amplified varying signaling-currents which consists in 130 causing a conductor to so move in a unipolar magnetic field, generated in whole or in part by the varying currents that the conductor and its line of motion shall each be at all

times at right angles to each other and the line of force which they cut, substantially as described.

5. The process of generating amplified telephone-currents which consists in causing a conductor to so move in a magnetic field, which is generated in whole or in part by a telephone-current, that the electromotive force generated in the moving conductor is independent of the position of the conductor within the magnetic field, substantially as described.

6. The process of generating amplified telephone-currents which consists in causing a conductor to so move in a magnetic field, which is generated in whole or in part by a telephone-current, that the electromotive force generated in the conductor is determined solely by variations in the density or sign of the magnetic field, taken as a whole, and not by the position of the conductor within the field, substantially as described.

7. The process of generating amplified tele-

phone-currents which consists in causing a conductor to so move in a magnetic field, 25 which is generated in whole or in part by a telephone-current, that the conductor, its direction of motion and the line of force which is cut shall at all times be each at right angles to the others, substantially as described. 30

8. The process of generating amplified telephone-currents which consists in causing a conductor to so move in a unipolar magnetic field, generated in whole or in part by the telephone-currents that the conductor and its 35 line of motion shall each be at all times at right angles to each other and the line of force which they cut, substantially as described.

In testimony whereof I have signed my name to this specification in the presence of 40 two subscribing witnesses.

JOSEPH B. BAKER.
